United States Patent Office

Des. 215,926
Patented Nov. 11, 1969

215,926

TELEPHONE ENCLOSURE

Rollie B. Nawman, Piedmont, Calif., assignor to Benner-Nawman, Inc., Oakland, Calif., a corporation of California

Filed Mar. 27, 1969, Ser. No. 16,481

Term of patent 14 years

Int. Cl. D25—99

U.S. Cl. D13—1

Fig. 1

Fig. 2

Fig-3

Fig-4

FIGURE 1 is a perspective view of the telephone enclosure showing my new design, the parts shown in phantom in all of the views form no part of the design;

FIGURE 2 is a front elevational view of the telephone enclosure shown in FIGURE 1;

FIGURES 3 and 4 are side and rear elevational views respectively of the telephone enclosure.

I claim:

The ornamental design for a telephone enclosure, substantially as shown and described.
